CLAIM

The ornamental design for a charging station, as shown and described.

DESCRIPTION

FIG. 1 is a front, top, left side perspective view of a charging station according to the invention.

FIG. 2 is a back, bottom, right side perspective view thereof.

FIG. 3 is a front elevation view thereof.

FIG. 4 is a back elevation view thereof.

FIG. 5 is a right side elevation view thereof.

FIG. 6 is a left side elevation view thereof.

FIG. 7 is a top plan view thereof; and,

FIG. 8 is a bottom plan view thereof.

The shading in the drawings does not depict surface ornamentation but illustrates the surface contours of the charging station.
